WATCHMAN'S TOUR SYSTEM AND TOUR STATION

Edward A. Schachinger, New York, N. Y.

Application December 24, 1947, Serial No. 793,679

30 Claims. (Cl. 177—360)

1

This invention relates to a watchman's tour system and to apparatus and devices utilized therein. The invention more particularly relates to a watchman's tour system utilizing tour stations of particular constructions for attaining the primary purpose of insuring that the watchman properly completes his tour and in each tour operates the tour stations in succession in a predetermined order.

In my prior Patent 2,376,389, reissued April 8, 1947, Re. 22,864, is disclosed a watchman's tour system utilizing a plurality of tour stations, the construction of the tour stations designated in the patent as "preliminary" stations and of the system being such that when all of the tour stations are properly actuated in a predetermined relation to each other a routine signal is transmitted upon operation of a transmitting station. The operation of any "preliminary" station in other than the predetermined manner produces an alarm signal.

In the patent it is suggested that, with the exception of certain "dummy" stations, combination changing locks may be used in the "preliminary" stations which require for the successive operations of each station a different key and it is proposed to provide all of these stations with locks of the same type. As the watchman proceeds on his tour with a given key, therefore, he may operate in succession the locks of all of the stations, changing the combination thereof from a given combination to the succeeding combination. In the succeeding tours, the watchman requires for all of the "preliminary" stations keys respectively corresponding to the succeeding combinations in order to operate the locks of the "preliminary" stations. A series of keys for this purpose, of course, may be controlled by a supervisor to insure that the watchman utilizes the proper keys for the respective tours. The patent also discloses a construction for the "preliminary" station which provides a key channel for releasing a key contained therein upon operation of the lock of the "preliminary" station.

While the system of my prior patent is effective for many purposes and conditions and especially where the routine and alarm signals may be given in a central station under supervision of a supervisor, it is desirable for some purposes to provide a simplified system which may be operated by the watchman alone. Such a simplified system may include an alarm signal which, if desired, may serve to alarm an intruder or, on the other hand, to notify a supervisor of faulty operation of the system or the need of assistance for the watchman.

2

It is an object of the invention to provide a watchman's tour system having tour stations operable by the watchman of such construction and arrangement that he must make his tour of these stations in a predetermined order.

It is another object of the invention to provide in such a system a transmitting station which may be operated only after the completion of the tour of the tour stations has been properly carried out.

It is a further object of the invention to provide a watchman's tour system in which the watchman is required to make his tour of the stations in a predetermined order and in which upon proper operation of the system and completion of the tour in the predetermined order a routine signal is produced, improper operation thereof producing an alarm signal.

It is a still further object of the invention to provide a watchman's system having a plurality of tour stations constructed with locks of the combination changing type to establish a predetermined sequence, means being provided in the system which enables the watchman to secure for the successive stations and subsequent tours the proper key for operation of the tour station locks.

It is an additional object of the invention to provide a watchman's tour system in which a transmitting station is utilized which is provided with a combination changing lock, the proper keys in succession being made available to the watchman for operation of this transmitting station by proper operation of the tour stations in succession, thus requiring that the watchman visit the tour stations in a predetermined order.

It is another object of the invention to provide a tour station of particular construction for a system capable of attaining the above objects of the invention.

It is a further object of the invention to provide a key magazine for a system utilizing combination changing locks which may serve as a tour station and which is operable by the watchman to secure the proper key of a set of keys for the successive operations of the locks.

It is an additional object of the invention to provide in the tour stations, the transmitting station and the magazine constructions for insuring against improper operation thereof and against tampering by intruders or unauthorized persons and to insure that the watchman shall operate the system in the desired order and the desired manner.

In its broad aspect the system of the invention utilizes at least one tour station and prefer-

ably a plurality of tour stations, together with a transmitting station, these stations being distributed about the site to be surveyed by the watchman. At least the transmitting station has a lock provided with means for changing the combination thereof in each operation of the lock and requiring a different predetermined key of a set of keys for the next operation of the lock. Associated with each tour station is means for releasably retaining a key of the set of keys for operating the transmitting station lock. This means is actuatable by a key of this set of keys to release the retained key.

Preferably the tour station is constructed with a key trap or channel which is adapted to receive a key of the set of keys for the transmitting station lock for passage of this key through this key channel. The tour station also is provided with means which cooperate with this key channel for releasably retaining the key inserted in the channel. This means is actuated upon such insertion in the channel of a second key of the set for conditioning the retained key for release thereof. The construction of these means is such that the keys must pass through the channel in succession. In the preferred form of the tour station, the retained key, however, is not immediately released upon insertion of the second key but means are provided which cooperate with the retaining means and with the means actuated by the inserted key for effecting release of the retained key only when the second key has been inserted in the channel and, as well, the station has been properly operated by the watchman. It will be understood that the preferred construction of the tour station is such that, regardless of the order in which the watchman carries out the sequence of steps in the operation of the tour station, he is required both to insert in the key channel a key of the set of transmission station keys, preferably a key from the immediately previously operated tour station, and then to operate the tour station which may be accomplished by a key or other suitable means. Only by completing these cooperating steps can the watchman secure from the key channel the retained key for insertion in the key channel of the next succeeding station of the tour. By carrying out the operation of the several tour stations in succession with the sequential insertion of the key from a preceding station in the channel of the station being operated the watchman progresses to the last tour station before reaching the transmitting or final station and there receives from the key channel the proper key for operating the transmitting station.

As will be more fully understood from the description to follow of the specific embodiments of the system of the invention in connection with the drawings, at the completion of each tour the watchman will have in hand a different transmitting station key, that is, the adjacent key in the order of the keys of the set, to that which he had in hand at the completion of the previous tour. Upon the completion, however, of a number of tours determined by the number of tour stations associated with a transmitting station, the watchman again will have in hand the same key with which he initially started the succession of tours. Since, as has been indicated above, at the completion of each tour the transmitting station lock is operated to transmit a signal or to make a record or for other purpose and the combination of the trans-

mitting station lock thereby is changed, it is necessary that the watchman have in hand at the completion of each of the successive tours the proper key for operation of the transmitting station lock which will effect the concomitant change of the combination thereof. This the invention accomplishes and the watchman is required to visit the tour stations in the proper order in order that he shall have in hand the proper key for operation of the transmitting station when he reaches this station in his tour.

Although the provision of tour stations constructed with a key channel and retaining means of this type itself is sufficient to insure the proper completion of the tour by the watchman for the purpose of securing the correct key for operating the transmitting station and to change the combination of the lock thereof, it is preferable to combine with the key channel and retaining means a lock operable in a forward and reverse movement which requires a particular key for its operation and the cooperation of the key inserted in the key channel in order to obtain release of the key for operating the subsequent tour station. The provision of tour stations of this construction affords a double insurance that the keys of the set of keys for operating the transmitting station will be maintained in the proper order and that the proper key will be available at the end of each of the successive tours for operating the transmitting station.

In one aspect of the invention the locks of the tour stations are of the combination changing type which are operable by a "supplemental" set of keys which may be different from that which is adapted to operate the transmitting station lock. In one embodiment of the invention in this aspect the locks of all of the tour stations may be alike and they may be set to the same combination at the start of an initial tour. The watchman, therefore, will carry with him a key which will change the combination from the set combination to the next succeeding combination and will so operate the locks at each of the tour stations. Upon completion of the tour, therefore, he will have changed the combination of all of the locks to the next succeeding combination which will require a different key for the operation of these locks in the next tour.

While the set of keys for operating the tour station locks may be under control of a supervisor from whom the watchman may obtain the next key, preferably in accordance with this aspect of the invention at a predetermined point with respect to the series of tour stations and the transmitting station means are provided for containing this "supplemental" set of keys. This containing means may take the form of a magazine which is capable of containing as a series all except one of the set of keys and is constructed so that upon insertion of the remaining key of the set, a predetermined key of the set will be separated from the series contained in the magazine and will become conditioned so that it may be withdrawn from the magazine when the magazine is properly operated as more particularly described hereafter. By use of such a set of "supplemental" keys and the means for containing them, it will be understood that the watchman may operate the system of the invention substantially without supervision, the construction of the devices utilized in the system being such as to prevent tampering and improper operation, and insuring that the watchman shall visit the tour stations in a predetermined order

and that he shall operate the transmitting station to transmit a signal or otherwise give an indication or make a record at the completion of his tour.

In another aspect of the invention, the tour stations are similarly constructed, preferably with a lock cooperating with the key retaining means, as above generally described, the system in this aspect utilizing a set of keys suitable for operation of a lock having a predetermined number of combinations, all of the locks of the tour stations and the transmitting station being operable by the keys of this set. In this embodiment, in order to insure that the proper key shall be available when withdrawn from the key channel of each tour station for operation of the lock of the next succeeding tour station and for the operation of the lock of the transmitting station in its sequence, a key containing means or magazine is utilized which is adapted to contain a "supplemental" set of keys which is the duplicate of the set which, as will be understood from the above general description, is distributed in the key channels of the tour stations. By providing the proper number of such magazines in addition to the tour stations and the transmitting station and the corresponding number of duplicate "supplemental" sets not only is the sequence of the keys of the set always maintained for successive operation of each lock, both of the tour stations and of the transmitting station in accordance with the change of the combination thereof in each operation of the lock, but the condition is insured that the watchman has in hand the proper key for the operation of the next tour station of the tour and, upon completing the tour, the proper key for the operation of the transmitting station.

The arrangement of tour stations and the transmitting station in relation to the magazines may be such that each tour station and the transmitting station shall have associated therewith a magazine. The construction of these magazines, as will be more fully understood from the description thereof in connection with the drawings, preferably is such that only one key may be inserted therein at a time and concomitantly only one key is separated from the series of keys within the magazine and conditioned for withdrawal therefrom. Moreover, the magazine preferably is constructed so that only a key of the set of keys with which it is associated may be inserted in the magazine for effecting withdrawal of the predetermined key therefrom. Means preferably are provided for insuring against improper operation of the magazine and for locking the magazine against operation except by the watchman who carries a key for this purpose.

In a further modification of the invention in the aspect thereof which utilizes only a set of keys for a single set of combinations of a lock and a "supplemental" set which is a duplicate of this single set of keys, the tour stations may be constituted only by magazines of the type above generally described. In such a modification the number of magazines required, in order that the watchman may obtain at the end of each tour the proper key for operating the transmitting station to transmit the signal or otherwise make a record and to change the combination of the lock of this transmitting station, will be equal to the number of keys (combination changes) utilized plus one. It will be understood from the more detailed description to follow of the invention in this further modification thereof that upon inser-

tion of a key carried by the watchman from one tour station to another in the magazine of the station at which he arrives he will be able to withdraw from the magazine the key which may be inserted in the magazine of the next succeeding station to receive from this magazine the key which may be inserted in the succeeding magazine. This sequence of insertions or withdrawals of the keys in the magazines which serve as tour stations continues until the watchman reaches the transmitting station where he utilizes the key withdrawn from the last magazine station to operate the transmitting station. The key utilized for this purpose then may be carried to the first tour station for insertion in the magazine thereof at the beginning of the second tour, each tour being carried out and completed in the manner described.

The details of the construction of the tour stations and of the magazines and the operation thereof and of the system when it is provided with signaling devices and signal transmission systems or circuits and other aspects and features of the invention will be more fully understood from the description to follow taken in connection with the drawings in which:

Fig. 1 shows diagrammatically the watchman's tour system of the invention utilizing a simple signaling system.

Fig. 2 shows the system of the invention with a modification of the signaling system.

Fig. 3 is a vertical section of the preferred form of the tour station of the invention taken transversely of the axis of the lock.

Fig. 4 is a vertical section taken on line 4—4 of Fig. 3.

Fig. 5 is a vertical section taken on line 5—5 of Fig. 4.

Fig. 12 is a horizontal section on line 12—12 of Fig. 9.

Fig. 13 is a section similar to that of Fig. 9 showing the positions of the keys as a key is inserted in the magazine.

Fig. 14 is a vertical section of a modification of the key magazine of the invention.

Fig. 15 is a plan view of the magazine of Fig. 14.

Fig. 16 is a vertical section on line 16—16 of Fig. 14.

Fig. 17 is a horizontal section on line 17—17 of Fig. 14.

Fig. 18 shows diagrammatically a tour system of the invention utilizing magazines as tour stations.

In Fig. 1 are shown five tour stations 1 identified as #1, #2, #3, #4, #5. Also in Fig. 1 is shown a transmitting station 3 and a key magazine 7. It will be understood that the five tour stations are distributed about the site in convenient or critical locations in order to insure that the watchman visiting them shall traverse the area to be surveyed. In the embodiment of Fig. 1 all of the five tour stations are of the same constructions and of similar appearance and are provided with key channels as generally described above for retaining, as diagrammatically shown in Fig. 1, respectively keys 10, 11, 12, 13 and 14 of a set of six keys. These keys hereinafter will be referred

to as "white" keys. The sixth "white" key 15 not shown in the drawing will be in the hands of the watchman, having been received from the tour station #5 upon insertion of the key 14. These "white" keys will be used for operation of the transmitting station 3.

This transmitting station may be constructed similarly to the transmitting station disclosed in my prior patent Re. 22,864 and may be provided with a combination changing lock, not shown in Fig. 1, operable by the proper "white" key, such as the key 15 withdrawn from tour station #5, to change the combination thereof. Such operation of the lock actuates the mechanism of the transmitting station including the code wheel 17 15 to operate contacts 19 connected in the circuit as shown in Fig. 1 in series with a routine signal across a source of electrical supply. Upon completion of the operation of the transmitting station 3, the watchman will take this same "white" key 15 and proceed to the tour station #1 for the next tour. At tour station #1, he will insert key 15 in the key channel thereof and upon operation of this station will be able to withdraw "white" key 10 from the key channel of tour station #1, as indicated in Table I. Upon such withdrawal, key 15 becomes trapped in tour station #1 and may not be released therefrom until this station again is operated, such operation requiring the insertion of a key of the set of "white" keys for operating the transmitting station and in the aspect of the invention being described in connection with Fig. 1 the operation of the lock 20 of station #1 by a "supplemental" set of keys in the manner to be described.

Upon withdrawing "white" key 10 from tour station #1, the watchman proceeds to tour station #2 and inserts key 10 in the key channel of tour station #2. Operation of the lock of tour station #2 concomitantly with such insertion of key 10 will condition "white" key 11 retained in tour station #2 for withdrawal therefrom. Upon such withdrawal, the watchman proceeds to tour station #3, inserts key 11, operates the lock of this station and effects withdrawal of "white" key 12 therefrom. Similarly, he operates in succession tour stations #4 and #5, ultimately withdrawing "white" key 14 from tour station #5. With key 14, he then may operate the lock of the transmitting station 3 again to transmit a routine signal, since key 14 will be the correct key for operation of the lock of the transmitting station in the combination to which this lock was operated by key 15, as previously stated. By operating the lock with key 14 the combination will be changed to that corresponding to key 13.

TABLE I

Tour No.	White Keys for Insertion in Tour Station Nos.	Change-in Lock Combination of Transmitting Station by White Keys					Change in Lock Combination of Tour Stations by Yellow Keys
		1	2	3	4	5	
1-----	{Insert.....15 10 11 12 13 Withdraw...10 11 12 13 14}	14 to 13	26 to 25	25 to 24	24 to 23	23 to 22	22 to 21
	{Insert.....14 15 10 11 12 Withdraw...15 10 11 12 13}						
2-----	{Insert.....14 15 10 11 12 Withdraw...15 10 11 12 13}	13 to 12	25 to 24	24 to 23	23 to 22	22 to 21	21 to 20
	{Insert.....13 14 15 10 11 Withdraw...14 15 10 11 12}						
3-----	{Insert.....12 13 14 15 10 Withdraw...14 15 10 11 12}	12 to 11	24 to 23	23 to 22	22 to 21	21 to 20	20 to 19
	{Insert.....12 13 14 15 10 Withdraw...13 14 15 10 11}						
4-----	{Insert.....11 12 13 14 15 Withdraw...12 13 14 15 10}	10 to 15	22 to 21	21 to 20	20 to 19	19 to 18	18 to 17
	{Insert.....10 11 12 13 14 Withdraw...11 12 13 14 15}						

8 changing combination in each station from a given combination, for example, that requiring key 26 to the next combination requiring key 25, is inserted in a key magazine to release the next "yellow" key 25 for operation of all tour stations in the next tour to change the combination from that requiring key 25 to the succeeding combination requiring key 24. In each succeeding tour the combinations are similarly changed requiring the succeeding "yellow" key which is obtained from the magazine, as more fully described hereinafter.

After transmitting the routine signal, the watchman then will take "white" key 14 to tour station #1 and insert it in the key channel thereof. Upon operation of the lock of tour station #1 in this second tour, he will withdraw "white" key 15. Proceeding to tour station #2, he will insert key 15 and concomitantly with the operation of the lock of tour station #2 will withdraw key 10. As shown in Table I, this sequence of steps will proceed through six tours upon completion of which the watchman again will have in hand "white" key 15 for operation of the transmitting station 3, the lock of this station having been changed successively to the six combinations for which it is constructed, as shown in the next to last column of Table I. Upon operation of the transmitting station 3 by key 15 at the end of the sixth tour, the combination of this lock again will be changed to that requiring key 14 for its operation, as above described. It will be apparent from the tabulation in Table I that the sequence of the keys of the set of "white" keys which are adapted to operate the lock of the transmitting station in its several combinations is maintained and that the proper "white" key always is available at the end of the tour for operation of this transmitting station lock.

For the operation of the locks 20 of the tour stations diagrammatically shown in Fig. 1, a separate or "supplemental" set of six keys 21, 22, 23, 24, 25, 26 is utilized. Five of these keys at a time are adapted normally to be retained in series in a magazine 7. These keys hereafter will be referred to as the "yellow" keys. In the particular embodiment of the invention being described in connection with Fig. 1, the locks 20 of the tour stations are alike and of the combination changing type and all have the same series of six combinations, thus requiring only one set of six keys as the "supplemental" set. The sixth key, which is additional to those normally contained at any given time within the magazine 7, is carried by the watchman who, upon visiting each station, operates the lock 20 thereof with the "yellow" key in hand. Thus, at each station in the respective tours, as shown in the right hand column of Table I, the combination is changed to the next combination requiring a different key for the operation of the station in the next tour. In the right hand column these combinations are indicated by the numerals "26" to "21," corresponding to the key numbers, the change in the combination being indicated in the decreasing order similarly to the order adopted for showing the change in combination of the transmitting station lock. Thus, the tour station locks 20 will be operated by key 26 in tour #1 to change the combination from 26 to 25. Upon completion of this tour, the watchman will insert key 26 in the magazine 7 as shown in Fig. 1. By such insertion, key 25 will be conditioned for withdrawal and the watchman will withdraw this key and use it during the next tour for operating

the lock 20 of each of the tour stations #1 to #5. Such operation of locks 20 will change the combination of each of these locks to the succeeding combination which corresponds to key 24. Upon reaching the transmitting station 3 which has the magazine 7 associated therewith at the end of the second tour, insertion of key 25 in the magazine will condition key 24 for withdrawal therefrom to make this key available for use in the third tour. As will be understood from Table I, upon completion of the sixth tour concomitant with insertion of key 21 in the magazine 7, key 26 will be conditioned for withdrawal therefrom to be available for operation of the locks in the succeeding tour, that is, the first tour of the second series of tours, which will correspond precisely both as to the "white" transmitting station keys utilized and the "yellow" keys for operation of lock 20 of the tour stations in a repetition of the sequences which have been explained above.

In Fig. 1 also is shown an auxiliary tour station 28 which may be of the same construction as the tour stations 1. The purpose of the auxiliary station is to produce an alarm signal whenever this station is operated. The tour station 28 may be provided with a key channel similar to that of tour stations 1 for releasably retaining a key 30 therein. The key 30 may be of such form that it is capable of being inserted in the keyway of the transmitting station lock and may be of the same appearance as though actually different from the "white" keys 10 to 15 inclusive which are distributed in the tour stations. It, therefore, may be inserted in any of the key channels and may be released therefrom in the same manner as any of the keys 10 to 15 inclusive. Upon release of the key 30 from the tour station 28, if this station is operated, the key 30 may be inserted in the next tour station, for example, the station #4 in Fig. 1 to effect release of the key 13. The key 13 then released may be inserted in the key channel of the tour station #5 and key 14 may be released upon operation of the lock 20 of this station. As shown in Table I, this key 14 may be used to operate the transmitting station as if the tour had been carried out in the normal manner.

The watchman may proceed after operating the transmitting station with key 14 successively to insert the keys in stations #1, #2, #3, 28, #4 and #5, and he will be able to complete this tour and operate the transmitting station with key 13. Key 30, however, at this time will have progressed to and be contained within tour station #5. Upon completion of the next tour at the end of which normally key 12 would be withdrawn from tour station #5 for operation of the transmitting station, key 30 will be withdrawn in its place. Even though the key 30 is insertable in the transmitting station keyway, it is of such form that it will not operate the lock of this transmitting station in any of the combinations thereof. It will be understood, therefore, that at the completion of this third tour the watchman will be unable to transmit the routine signal and if transmission does not occur within the time allotted for the tour, such departure from the routine will be observed at the signal station or recorded on a suitable recording instrument operated by the signaling device connected to the transmitting station.

The description above given with respect to the auxiliary station concerns its operation without having associated therewith a transmitting

element, as shown in Fig. 1, which may comprise a code wheel 32 for operation of contacts 33. The code wheel 32 may be operatively connected to the lock, not shown, of the auxiliary station 28, the contacts 33 being connected with an alarm signal device across the electric supply. The lock of the tour station 28 may have a keyway for receiving any of the "yellow" keys 21 to 26 inclusive and may be operatively connected to the code wheel 32 so that this code wheel is operated when the lock of station 28 is operated by any of the "yellow" keys. It will be understood, therefore, that when the tour station 28 thus constructed and connected in the circuit with the alarm signal device is operated in precisely the same manner as any of the tour stations 1 not only will release of the false key 30 be effected but an alarm signal will be produced which may be immediately observed by a supervisor at the central office or signal station at which also the routine signal device may be located. This will enable the supervisor immediately to inform the watchman that he has improperly operated the succession of tour stations.

If, however, an unauthorized person attempts to operate the stations, even though he succeeds in successively inserting and withdrawing the keys from the tour stations #1, #2 and #3, he will be unable to determine that auxiliary station 28 contains the false key or that it is provided with an alarm transmitting device. If the system utilizes an auxiliary station 28 without the alarm transmitting device 32, 33, as explained above, during the course of the successive tours, the false key will progress to the transmitting station but will be incapable of operating this station to transmit the routine signal. The absence of this routine signal within the required time assigned for a tour will indicate to the supervisor that the system is not being properly operated and that investigation is required. If in the auxiliary station 28 the alarm signal transmitting device 32, 33 is provided, immediate investigation may be made upon the actuation of the alarm signal device in the supervising office. It will be understood that the auxiliary station 28 may be located in any relation in the tour to the other tour stations and to the transmitting station requisite to produce the indication of improper operation or the alarm after operation of a desired number of tour stations or time interval.

It will be understood further that if the watchman desires to send an alarm signal in the case of an emergency, he may do so by operating the lock of auxiliary station 28. In such case, it is not necessary for him to insert the particular key 12 withdrawn from station #3 in the key channel of auxiliary station 28. Since the locks 20 of the tour stations and that of the auxiliary station 28 in the embodiment being described all are operated by the same key of the set of "yellow" keys, the insertion of the "white" key in hand in the key channel of station 28 and the operation of its lock by the "yellow" key in hand insures operation of auxiliary station 28 and the sending of the alarm. The normal sequence of the "white" keys 10 to 15 inclusive then may be resumed after transmitting the alarm signal by again inserting key 30 in station 28 to release the regular "white" key inserted for alarm purposes.

As an additional aid to the watchman, a similar alarm signal transmitting station 35 may be located adjacent the normal transmitting station or elsewhere in the area surveyed and may

be provided with a code wheel 36 and contacts 37 connected to the alarm signal device at the supervisor's office in parallel with the alarm transmitting device 32, 33 of auxiliary station 28. In order to indicate to the watchman that his alarm signal from the station 35, especially if adjacent the transmitting station 3, has been or is being transmitted, a local signal device such as a bell 39 may be connected in parallel with the alarm signal device for simultaneous operation therewith. The alarm signal station 35 need not be provided with a key channel since the sequence of keys for operation of the transmitting station 3 is accomplished in the tour stations #1 to #5 inclusive. If desired, however, the alarm signal 35 may be combined in a single casing with the magazine 7 or this magazine may be combined with the transmitting station 3 or, further, a combination of these three members 3, 7, 35 may be made in a single structure.

In Fig. 2 is shown a tour system having five tour stations #41, #42, #43, #44, #45 corresponding respectively to stations #1 to #5 inclusive in Fig. 1 and having key channels for releasably retaining the "white" keys 10 to 15 in the same manner as described in connection with the tour stations of Fig. 1. The watchman having in hand at a starting time a key 15, the succession of keys inserted and withdrawn in the key-way channels of stations #41 to #45 inclusive in Fig. 2 will be precisely the same as that set out in Table I. Moreover, the transmitting station 47 will be provided with a combination changing lock capable of being operated by a set of "white" keys 10 to 15 inclusive in the same manner as transmitting station 3 in Fig. 1.

In this embodiment also the tour stations #41 to #45 inclusive are provided with locks 20 operable by a set of "yellow" keys 21 to 25 similarly to the locks 20 in Fig. 1. The locks 20 of tour stations #42 and #45 and transmitting station 47, however, are not shown in Fig. 2 in order without confusion diagrammatically to represent the routine and alarm signal transmitting devices associated with these three stations. The sequence of operations of the locks 20, however, in the tour stations #41 to #45 inclusive in Fig. 2 may be precisely the same as that set out in the right hand column of Table I, the combination of each tour station lock being changed in each tour from a given combination to the next combination requiring for the operation of these locks in the succeeding tour a key corresponding to such succeeding combination.

The routine and alarm signal transmitting devices associated with tour station #45 is generally the same as those associated with the normal "preliminary" or tour stations as disclosed in my prior patent Re. 22,864. By operation of the lock 20 of station #45 by a "yellow" key, a cam 51 is actuated, for example, from the vertical position shown in Fig. 2 90° to a horizontal position to change the contact 53 from engagement with contact 55 to engagement with contact 57. Correspondingly the contact 59 in the transmitting station 47, by operation of the lock thereof with a "white" key to move cam 51 from the vertical position shown 90° to the horizontal position, is changed from engagement with contact 61 to engagement with contact 63. As will be observed by tracing the circuit from the source of electrical supply, the routine signal will be energized when the circuit is established through the contacts 65, 66 of the transmitting station which are actuated by the code 67, contacts 59,

63 of the transmitting station and through contacts 69, 71, of tour station #42, as well as through the selector switch 73 in the position shown in Fig. 2; this selector switch making contact with the terminals 74, 75, 76. To secure this routine signal the contact 69 of station #42 must be thus actuated by a cam 51 when the cam 51 is rotated 90° from the vertical position by operation of the lock 20 of station #42. It thus will be understood that the operation of stations #45 and #42 to rotate the cams 51 thereof from the vertical to the horizontal and thereafter the operation of the transmitting station 47 to rotate its cam 51 from the vertical to the horizontal will produce a routine signal in the same manner as described in my prior patent. Similarly, operation of tour stations #45 and #42, with the selector switch set as shown in Fig. 3 to move cam 51 from the horizontal to the vertical position with subsequent operation of the transmitting station 47 to move its cam 51 from horizontal to vertical, will produce a routine signal. As many tour stations #41, #43, and #44 as is desired may be provided simply with contacts 53, 55, 57 which are shown in Fig. 2 for station #45.

It will be understood from a consideration of the system disclosed in the patent Re. 22,864 that station #42 is one of the stations described in the patent which when the selector switch 73 is in the position shown in Fig. 2 operates as a normal station but which may become a "dummy" station. Station 49 is another station which, when selector switch 73 is in the position shown in Fig. 2, is a "dummy" station but which may become a normal station by changing the position of the selector switch 73 so as to make contact with terminals 76, 77 and 78. Thus, in the normal operation of the system disclosed in Fig. 2 when the selector switch 73 is in the position shown, station #42 operates as a normal station in which only contacts 68, 69, 71 are in circuit. When the selector switch is moved to engage terminals 76, 77 and 78, station #42 becomes a "dummy" station and station 49 becomes a normal station in which contacts 68, 69, 71 similar to those of station #42 are in circuit.

In each of these stations #42 and 49 contacts 80 are provided which are operated in the normal operation of the station by means of the key in the lock 20 to move the cam 51 from the vertical position shown to the horizontal position at 90° therefrom or the reverse. When the selector switch 73 is in the position shown in Fig. 2, the station 49 being a "dummy" station, the contacts 80 of station #42 operating as a normal station are ineffective since the circuit therethrough is open at the terminal 77. The contacts 80 of station 49, however, become connected in circuit with the alarm signal device at the central office if the lock of station 49 is operated to rotate its cam 51 from the vertical position shown in Fig. 2 to the horizontal position at 90° therefrom. This circuit is traced through the alarm signal, contacts 80 of station 49, terminals 75, 74 of switch 73, contacts 69, 71 of station #42 when its cam is operated to horizontal position, contacts 63, 59 of the transmitting station 47 when its cam is operated to horizontal position, and contacts 66, 65 of the transmitting station. If the selector switch 73 is changed to make contact with terminals 76, 77, 78 and station #42 becomes the "dummy" station, the contacts 80 of station #42 are connected in the alarm circuit and the alarm will be given on operation of the transmitting station.

The "dummy" station also may be constructed to contain the false key 30 as described in connection with station 28, Fig. 1. Operation of the "dummy" station by an unauthorized person, therefore, may involve not only the development of a false sequence by insertion of "white" key 13 in station 49 to effect withdrawal of the false key 30 and the subsequent arrival of the false key 30 at the transmitting station in a manner similar to that described in connection with Fig. 1, but may produce an alarm signal in the manner just described. Station 49, like station #42, may be constructed to be operated by a "yellow" key of the set of keys utilized for operating the locks 29 of the several tour stations and effective to change the combinations of these locks in each operation thereof. The shape, size and appearance of stations #42 and 49 may be the same as those of the other tour stations to prevent an intruder distinguishing therebetween.

Diagrammatically shown in Fig. 2 is a key magazine 7 containing the series of keys of the set of "yellow" keys except the key which is in the hands of the watchman. The construction and operation of the magazine 7 may be the same as that described generally in connection with Fig. 1 and this magazine may be placed in any suitable place in the tour. It also may constitute a tour station which will cause the watchman to visit a particular location in order to be able to maintain the proper key sequence by insertion and withdrawal of the "yellow" keys to and from the magazine. If desired, the size, shape and appearance of this magazine may be the same as that of the tour stations and it may be provided, if desired, with a key channel not intended to be used in which an intruder or unauthorized person would be induced to insert a "white" key in the same manner as in the normal tour station, thus interrupting the normal sequence of the "white" keys for the operation of the transmitting station 47.

In Figs. 3, 4, 5 and 6 is shown the construction of the tour station #45 of Fig. 2. As above stated, the construction of this tour station may be substantially the same as that of the tour stations #1 of Fig. 1 with respect to the key channel and the means for releasably retaining a "white" key and with respect to the cooperation with this retaining means of the lock 29 operated by a "yellow" key. As shown in Fig. 3 the tour station #45 includes the contacts 53, 55, 57 shown diagrammatically in Fig. 2, the contact 53 being actuated by the cam 51 to control in cooperation with the other tour stations the transmission of a routine signal or an alarm signal depending upon the relative positions of the cams 51, that is, of the contacts actuated thereby, in the several stations at the time when the transmitting station 47 is operated. Cam 51 is carried on shaft 85 operatively engaged by the keyway shaft 87 of a combination changing lock 89 which may be of the construction shown in my prior Patent 2,427,814, September 23, 1947. The shaft 85 and the lock 89 are suitably supported in a casing 91. The construction and arrangement of the parts in the tour station #45 operable by the lock may be generally the same as that disclosed in my prior Patent Re. 22,864 and in my copending application, Serial No. 594,232, filed May 17, 1945, now Patent No. 2,486,439 issued Nov. 1, 1949, which is a division of the application upon which said Reissue Patent 22,864 issued. Certain other parts, however, are included in the lock station of this invention which perform functions and

accomplish purposes not disclosed in my prior patents and application.

Within the casing 91 of the tour station #45 a key channel 93 is formed by walls 94, 95 cooperating with the casing 91 to provide a channel of limited dimensions in the cross-section thereof to receive only a "white" key 96 of the set which is utilized for operation of the transmitting station in Figs. 1 and 2. As shown in Figs. 3 and 4, the key channel 93 extends vertically parallel to the backwall of the casing 91 from a slot opening at the upper wall 97 of the casing 91 to and through the bottom wall 98 thereof. Except for retaining mechanism about to be described, a key 96 dropped in the upper opening would fall through the channel lengthwise thereof and drop out at the opening in the bottom wall 98. Pivotally supported on in depending relation to pin 99 fastened in brackets 101 fixedly supported on the forward wall 95 of the key channel is a finger carrying member 103. Adjacent the pivot pin 99 this finger carrying member 103 carries an intercepting bar 105 adjustably fastened by screws 104 passing through vertically extending slots in finger member 103. The bar 105 projects from the member 103 through a slot 106 cut in the wall 95 of the key channel 93. The positions of the pivot 99 and the bar 105 in relation thereto and of both in relation to the upper wall 97 of the casing 91 are such with respect to the length of a "white" key 96 (shown in dotted outline in the upper position in Fig. 4) inserted in the key channel 93 at the upper opening thereof that the key 96 engages the bar 105 before this key becomes positioned fully within the key channel below the wall 97. The lower end 107 of the key 96 engages a beveled upper surface of the bar 105 pivotally to move the member 103 against the bias of a spring 109 which has a torsion portion thereof wound around the pivot pin 99 and legs 110 engaging the wall 95 of the key channel 93 on the opposite side of the pivotal pin 99 to bias the bar 105 to the position within the slot 106 and within the key channel. Adjacent the lower end of the finger carrying member 103 this member carries a pair of fingers 111. When the member 103 is moved counterclockwise in Fig. 4 under the bias of spring 109 the fingers 111 move toward the right respectively to pass through holes 112 in the forward wall 95 of the key channel to intercept the key 96 when it shall have passed by the bar 105 and dropped to a position where it may be engaged by the fingers 111 with the shank of the key extending between these fingers so that the head of the key is supported thereby, as shown in the dot and dash outline in Fig. 3. This is the position which the key 96 retained in the key channel takes when the operation of a tour station is completed and the previously inserted key has been withdrawn therefrom for operation of the next tour station. When another "white" key is inserted in the upper opening of the key channel 93 and the lower end 107 of such other key engages the bar 105, the fingers 111 will be moved outwardly of the holes 112 toward the left in Fig. 4 and the key 96 supported on these fingers 111 may drop further in the key channel to the positions shown in the lower dotted outline, Fig. 3, full lines, Fig. 4, where it will be engaged by means about to be described so that it cannot be withdrawn from the key channel except upon operation of the lock of the tour station in the manner to be described. Pivots supported on brackets 115 fastened

to the back face of the rear wall of the casing 91 is an auxiliary finger carrying member 117. The member 117 is biased to pivot in the counter-clockwise direction in Fig. 4 by a spring 119, having a torsion portion thereof wound upon the supporting pin 120, the ends of which engage respectively the back face of the casing 91 and the adjacent surface of the auxiliary member 117 at opposite sides of the pivotal pin 120. The member 117 carries a pair of fingers 121 which may pass through holes 123 in the rear wall of the casing 91 to enter the key channel upon movement of the auxiliary member 117 clockwise against the bias of the spring 119. By means to be described such clockwise movement of the auxiliary finger carrying member 117 is effected concomitantly with movement of the finger 111 of the finger carrying member 103 toward the left as above described, the fingers 121 intercepting in the lower dotted position in Fig. 3 the key released from the fingers 111 so as to prevent withdrawal of this key at the lower opening of the key channel in the wall 98. The fingers 121 may be formed with inclined surfaces to conform to the slope of the bottom edges of the head of the particular form of "white" keys utilized in the system being described. The end of the shank of this key in this lower position may project through this lower opening so that when the auxiliary finger carrying member 117 is moved reversely, that is, in the counterclockwise direction to move the fingers 121 toward the right in Fig. 4 out of the key channel 93, the lower key may drop from the position where the head thereof is engaged by the fingers 121 to engagement with spring retainers 125. These spring retainers 125 are so formed that pull exerted on the key the head of which rests thereon will move the spring members aside sufficiently to enable the head of the key without great resistance to pass by these spring retainers in frictional engagement therewith and with the rear wall of the key channel.

For the operation of the auxiliary finger carrying member 117 to move the fingers 121 thereof into key intercepting position in the key channel 93, this member 117 is formed with a gooseneck 127 at the upper end thereof which projects through the rear wall of the casing 91 alongside of the key channel, as may be seen in Figs. 3, 4 and 6. The retroverted portion of 128 of this gooseneck thus normally is positioned within the casing 91 and is engageable by a cam finger 129 fastened upon the shaft 85 as shown in Figs. 3, 5 and 6. Upon rotation of the shaft 85 in the normal operation of the lock forwardly, that is, clockwise in Figs. 3 and 5, the cam finger 129 engages the retroverted portion 128 of the member 117 and moves this member counterclockwise in Figs. 4 and 6 upon the pivot pin 120 against the bias of the spring 119. The position of the member 117 when so actuated by the cam 129 is that shown in Fig. 6 with the fingers 121 in key intercepting position within the key channel 93. When the lock is reversely operated, that is, counterclockwise in Figs. 3 and 5 to rotate the cam finger 129 back to the position shown in Fig. 3 from that shown in Fig. 5, the auxiliary finger carrying member 117 is returned under the bias of spring 119 to the position shown in Fig. 4. Such reverse movement, however, may not take place for reasons which now will be explained until a "white" key has been inserted in the upper opening of the key channel to actuate the finger carrying member 103 to

move clockwise in Fig. 4 against the bias of the spring 109.

To prevent return movement of the cam finger 129 until a "white" key is inserted, a locking cam 131 is fastened upon the finger carrying member 103 and moves toward the left in Figs. 4 and 6 out of the path of travel of the cam finger 129 in the clockwise movement of member 103, thus to permit the return movement of this cam finger 129 to the position shown in Fig. 3. The form of the lower surface of the locking cam 131 in relation to the form of the upper surface, Fig. 6, of the cam finger 129 is such that as the cam finger 129 is rotated clockwise in Fig. 3 in the operation 15 of the lock 89 of the tour station the locking cam 131 is moved by the cam finger 129 toward the left in Figs. 4 and 6, thus moving the fingers 111 out of their position within the key channel. In this movement cam finger 129 passes above 20 the locking cam 131 and cannot return until cam 131 is moved out of its path. In the movement of cam 131 toward the left, Fig. 4, the key 96 carried on the fingers 111 will be released therefrom to fall further through the key channel. 25 Thus, the key 96 may be released from fingers 111 either by insertion of a "white" key, as above described, or by the initial operation of the lock. In this upward movement of the cam finger 129 the fingers 121 move into the key channel and 30 these fingers 121 are effective to intercept and engage the head of the key in the lower dotted position shown in Fig. 3, full lines in Fig. 5. As long as the cam finger 129 is prevented by locking cam 131 from returning in the counterclockwise 35 direction in Fig. 3 and downwardly in Fig. 6, the key is retained by the fingers 121 and may not be withdrawn from the lower opening of the key channel 93.

The spacing of the fingers 121 below the bar 40 105 preferably is such in relation to the length of the key 96 and of its head that this key when released by bar 105 may drop free thereof and stand with its toe upon the head of the key below which is supported on fingers 121. These positions of the keys are shown in Fig. 3 respectively in the upper dotted outline of key 93 and in lower dotted outline, Fig. 3, and full line, Fig. 5.

The form of the upper surface of the locking cam 131 with respect to the form of the lower 45 surface of the cam finger 129 in such that the cam finger 129 may not be moved downwardly in Fig. 6, that is, counterclockwise in Fig. 5, to pass the locking cam 131 unless this locking cam is moved at least part way toward the left in Fig. 55 6 toward the position where it is out of the path of movement of the cam finger 129. This initial movement may be accomplished by insertion of a "white" key to engage the bar 105. It now will be understood that when the lock of the tour 60 station is operated by a "yellow" key forwardly to effect the change in the combination thereof this lock may not be reversely operated until a "white" key is inserted in the key channel; also that the "white" key which has been retained 65 within the key channel 93 cannot be withdrawn from the channel for insertion in the next tour station until the "white" key from the previous tour station is inserted in the upper opening of the tour station being operated. Preferably also the "yellow" keys and the lock 89 are so formed that the key cannot be removed from the lock 89 except in the initial position, that is, when the cam finger 129 is in the position of Fig. 3. When these steps of operation have been carried 70 out the "white" key inserted in the upper open-

ing will be conditioned to drop to the position in which the fingers 111 will engage the head thereof and the "white" key which has been retained in the key channel will be released by the fingers 121 for withdrawal past the spring retainers 125.

When by insertion of a "white" key the initial movement of locking cam 131 toward the left, Fig. 4, is produced, downward movement of the cam finger 129 brings the bevel surface 133 thereof, Fig. 6, into engagement with the bevel surface 135 of the locking cam 131 to produce a further movement of the locking cam 131 toward the left concomitantly with movement of the bar 105, Fig. 4, outwardly of the slot 106. This will relieve or remove the frictional contact of the bar 105 with the inserted key 96 to release this key to drop into the space within the key channel beneath the bar 105, that is, to the upper dotted position, Fig. 3, resting on the head of the lower key (dotted) which now is carried by fingers 121, this lower key having reached this position by virtue of release from fingers 111 in the upward movement of cam finger 129 or by insertion of the new "white" key. The inserted key, therefore, cannot drop below the fingers 111 because, in the reverse movement of the lock, counter-clockwise, Fig. 3, the cam finger 129 in its downward movement will pass the locking cam 131 and will permit movement of this locking cam toward the right concomitantly with movement of fingers 111 into the key channel before the cam finger 129 moves out of engagement with the retroverted part 128 of the auxiliary finger carrying member 117 to move the fingers 121 out of the key channel. The lower key held by fingers 121, therefore, supports the upper key 96 until the fingers 111 are beneath the head of key 96.

In the apparatus of my prior patent Re. 22,864, the lock station was constructed so that the cam 51 was continuously moved step by step in the same direction for rotation in the successive operations of the lock. While such a construction may be utilized, in the embodiment of the invention being described the shaft 85 is given a reciprocating angular movement corresponding to that of the keyway shaft of the lock concomitant with the change in the combination of this lock. Nevertheless, the cam 51 is effective to actuate the contact 53 to and from engagement with the contacts 55 and 57 for the purpose of transmitting a routine signal or an alarm signal, as the case may be, depending upon the construction of the tour station as described in connection with stations #42, #45 and 49 of Fig. 2.

The construction of the tour station shown in Figs. 3, 4, 5 and 6 is such that the watchman is not required to follow a particular order with respect to the initial operation of the lock by the "yellow" key in the forward direction and the insertion of the "white" key in the upper opening of the key channel 93. He may take either of these initial steps first. If, however, he inserts the key in the key channel 93 and pushes it down with its head below the upper opening so that it cannot again be withdrawn, this key may be held by the pressure of the bar 105 from dropping to the upper dotted line position, Fig. 3. If the watchman then operates the lock clockwise, Fig. 3, the key which has been retained within the key channel will drop to engagement with fingers 121 and cannot be withdrawn from the key channel 93 at the bottom opening thereof. As above explained, however, by the action of cam finger 129 on the lock-

ing cam 131 the key 96 will be released from bar 105 and will fall to the position with its toe resting on the head of the retained key, the shank of this retained key projecting from the lower openings of the key channel. Thus there will be located within the channel 93 two "white" keys. The "yellow" key also cannot be withdrawn from the lock nor can the lock be reversely operated because of the interference by the locking cam 131. In order to secure release of the projecting "white" key, however, it is merely necessary that the watchman push this projecting key upwardly, thereby to push upwardly the key 96 resting thereon until the head of this upper key engages the lower beveled surface of the bar 105, as shown in Fig. 4, to move the finger carrying member 103 clockwise and thereby to move the locking cam 131 toward the left sufficiently to enable the surface 133 of the cam finger 129 to engage the surface 135 of the locking cam 131. Reverse movement of the lock, with concomitant camming action of surfaces 133, 135 to move the locking cam 131 out of the way, then will become possible to the initial position of the lock in which the "yellow" key may be withdrawn therefrom.

In Figs. 7 to 13 inclusive is shown the construction of a magazine, such as the magazine 7 diagrammatically shown in Figs. 1 and 2. This magazine in the embodiment of Figs. 7 to 13 inclusive comprises an outer casing 140 upon which is hinged a door 141 which may be provided with a lock 143 having a latch 144 engageable with an opening in the side wall of the casing 140, which opening may be covered by a portion 145 of the door 141 when this door is in the closed position so that access may not be had to the latch. For the operation of the lock 143 the watchman may carry a special key.

By means hereafter described, the door 141 of the outer casing is biased to open position. This door is provided with a slot 147 through which projects a pin 149 carried by a member 161 of the internal mechanism of the magazine, this pin being operable in the direction from left to right in Figs. 7 and 8 through a slot 150 in an inner shell 151 of the magazine registering with slot 147 when the door is closed. The length of the pin 149 is such that the door 141 must be in the closed position in order that the outer end of the pin 149 shall project through the slot 147 for operation of the magazine. In order to prevent removal of the pin 149 by unscrewing from the pivotally supported member 161, the pin 149 is provided with a flange 152 of larger diameter than the width of the slot 147. This aids in preventing tampering with the internal devices of the magazine and insures operation of the magazine in the manner about to be described only when the door is closed.

As shown in Figs. 8, 9, 10 and 13 the upper wall of the outer casing 140 is provided with a slot 153 registering with a slot 155 in the upper wall of the shell 151. Fastened upon the door 141 adjacent the upper edge thereof is a slot closing plate 157 of sufficient width, as shown in Fig. 9 and as shown in dot and dash outline in Fig. 12, to cover the slots 153 and 155 when the door is closed. The upper wall of the shell 151 is spaced somewhat from the upper wall of the outer casing 140 so that the long leg, Fig. 10, of the plate 157 may pass between the casing 140 and the shell 151 in the movement of the door between the open and closed, the plate 157 being moved clear of the slots 153 when the door is open, as shown in Fig. 13. Fastened in the upper wall of the outer

19

casing 140 and projecting inwardly thereof is a stop pin 158 which engages the plate 157 and limits the movement thereof in the opening movement of the door, thereby determining the open position of the door.

When the lock 143 is unlocked and, by opening the door 141, the plate 157 has been moved from its position closing the slots 153, 155, the "yellow" key carried by the watchman for operation of the locks of the tour stations 1 of Fig. 1 and tour stations #41, #42, #43, #44 and #45 of Fig. 2 may be inserted through the slots 153, 155, as shown in Fig. 13, upon completion of a tour. This key is inserted between the series of five keys contained in the shell 151 of the magazine and the member 161 which is pivotally supported upon a pin 163 carried in brackets 165 fastened to the side walls 166 of an inner container 167 which is formed so that it may be inserted in the shell 151 through the bottom of this shell which is left open. As shown in Figs. 10 and 11, the inner container 167 also is open at the top and this container and the shell 151 are in telescoping relation to each other. The bottom wall of the inner container 167 and the lower edges 154 of the shell 151 are spaced somewhat from the bottom wall of the casing 140 to provide space for means, hereafter described, for preventing withdrawal of a key until the magazine is properly operated by the insertion of the "yellow" key which has been carried by the watchman in completing the tour. After the inner container 167 has been inserted within the shell 151, the pin 149 may be screwed into the pivoted member 161, the pin 149 being provided with a shoulder 156 bearing against the side of the member 161, as shown in Fig. 7.

It will be understood that the slots 153, 155 are located in the upper walls respectively of the shell 151 and the outer casing 140 so that the end of a key 171 inserted therethrough will extend into a cavity 173 formed in the upper portion of the pivoted member 161. The key so inserted thus may be moved downwardly into the angle formed by the wall of this cavity and the upper portion of the adjacent key 175 of the series of five keys contained within the magazine. Continued pressure on the key 171 forces it down almost to the position shown in Fig. 13 which is effective to release the key 171 at the opposite end of the series of five keys. Such release is accomplished under the pressure referred to by the release of the lower end or toe of the key 171 from the position behind the upturned bead end 179 of a spring clip 180, fastened by screw 181 through the wall of the inner container into the horizontal leg of an upstanding bracket 183 hereafter further described. The pressure upon the key 171 as it is inserted brings a downward pressure of the series of five keys on the spring clip 180. Movement, however, of the key 171 is resisted by the friction of the end wall 185 fastened to the shell 151, this wall in the particular embodiment being described cooperating with the side walls 166 of the inner container 167 to close the key confining space at a lateral side of the inner container. The end 179 of the spring clip 180 thereby is moved downwardly sufficiently relative to the lower end of the key 171 to permit this key under the lateral pressure of the intervening four keys to move toward the left in Figs. 9 and 13 and to bear against the end wall 185.

The key 171 inserted in the magazine acting on the inclined surface of the cavity 173 moves the pivoted member 161 against the bias of the

20

helical compression spring 187 having one end thereof in a countersink formed in the member 161, the other end of this spring bearing against a washer 188 carried on a pin 189 which is threaded at its left end in and shouldered against the bottom surface of the countersink in the member 161. The pin 189 extends through a slot 191 formed in the upstanding leg of the bracket 183. This pin is provided with a head 193 at the outside face of the bracket 183, the washer 188 bearing on the bracket of the inside face under the pressure of the spring 187. It thus will be apparent that the spring 187 is effective to bias the series of keys to move toward the left in Figs. 9 and 13 and that the insertion of the key 171 will compress the spring 187. This spring, upon release of the key 171 at the lower end thereof from the bead end 179 of the spring clip 180, will produce quick movement of the key 171 into position above the lower opening 195 in the bottom of the inner container and the lower opening 197 in the outer casing.

When the key 171 is in the position shown in Fig. 9 with the end thereof projecting through the openings 195, 197, it may be withdrawn from the magazine. Initially, however, when the inserted key 171 takes its position in the series, there will be six "yellow" keys within the magazine, as shown in Fig. 13, and the friction creating pressure of the spring 187 will tend to restrain all these keys against vertical movement so that the shank of key 171 does not immediately drop through the openings 195, 197. Only when the door 141 has been closed and the pin 149 projecting through the slot 147 has been moved by hand toward the right in Figs. 7 and 8 to move the pivoted member 161 against the bias of the spring 187 is the pressure of this spring 187 upon the series of keys reduced sufficiently to permit the key 171 to drop through the openings 195, 197. It is necessary, therefore, that the watchman close the door of the magazine and operate the pin 149, in order to be able to withdraw from the series of keys the proper "yellow" key for operation of the locks 20 in the next tour; that is, for operating these locks in the combination to which they have been operated in the tour just completed.

As shown in Figs. 10 and 11, the keys within the container 167 move forward toward the releasing position between the sloping side walls 199, provided by a piece bent in V form and fastened by the screw 181 to the bottom wall of the inner container 167. These walls 199 may conform, as shown, generally to the shape of the head of the key and the width of the toe thereof.

Withdrawal, however, of the next "yellow" key cannot take place in the embodiment of Figs. 7 to 13 inclusive until the door is closed, means being provided for closing the openings 195, 197, 60 when the door is open. Cam plate 201 having an outline as shown in Fig. 12 is pivotally supported on pin 202 and is biased by spring 203 having a torsion portion wound about stud 204, the spring 203 having one leg thereof bearing against the cam plate 201 and the other end thereof bearing against the wall of casing 140. As shown in Figs. 9 and 13, the cam plate 201 operates in the space between the bottom wall of the inner container 167 and the bottom wall of the casing 140. As shown in Fig. 12, when the door 141 is closed the horizontally extending leg of a bracket 206 carried by this door engages edge 207 of the cam plate 201 and holds the cam plate 201 in the full line position uncovering opening 197. When the door is in open position, pressure by the bracket

206 is relieved and the spring 203 is effective to move the cam plate 201 to the dot and dash position shown in Fig. 12 to cover the opening 197 to prevent withdrawal of the key 171 until the door again is closed. The spring 203 also acts to bias the door to open position. For convenient operation, therefore, the watchman will close the door and lock it in its closed position after inserting key 171 in order that his hands may be free to operate the pin 149 to release the key 171 desired for operation of the tour station locks in the next tour. He cannot, moreover, obtain key 171 until the door is closed.

Such operation of the pin 149 to release the key 171, however, does not cause this key directly to drop from the magazine through the openings 195, 197. To prevent such occurrence within the inner container 167 and fastened to the side walls thereof are springs 209 having the lower portions thereof extending diagonally toward the center line of the magazine, as shown in Figs. 10 and 11. When the key 171 is released upon relieving the pressure of the spring 187 by operating the pin 149 this key will drop so that the head thereof, which may be formed as shown in Fig. 10 of trapezoidal form, is engaged by the springs 209 and retained from falling through the openings 195, 197 until the watchman is ready to pull it through these openings, the springs 209 yielding laterally for this movement. The form and position of springs 209 may be such as suits the form of the "yellow" key utilized.

It will be understood as shown in Fig. 13 that, when the key 171 is inserted in the slots 153, 155, it must be pushed down so that the upper edge of the head thereof substantially is below the space between the upper wall of the shell 151 and the upper wall of the casing 140 in order that the plate 157 may pass over the openings 153 and 155 to the position fully covering these openings when the door is in closed position. To insure such full insertion, the upper edge of each key may be slightly beveled and the edge of the plate 157 may be correspondingly beveled, as shown in Figs. 9 and 13, so that, if the upper edge of the key is not below the upper surface of the shell 151, the bevel edge of the plate 157 will engage the bevel edge of the key 171 and force this key downwardly sufficiently to permit the plate 157 to pass, provided the key has been pushed down sufficiently for such engagement. Moreover, as the form and arrangement of the cam plate 201 and the bracket 206 cooperating therewith are such that the key 171 cannot be withdrawn through the opening 197 until the door is fully closed with the bracket 206 pressing upon the cam against the bias of spring 203, as shown in Fig. 12, it will be understood that the key 171 cannot be withdrawn from the magazine until the key 171 has been inserted in the magazine to such an extent that it cannot thereafter be withdrawn therefrom.

Correspondingly, as the plate 157 covers the openings 153, 155 until a substantial movement has been given to the door toward its open position, such movement is effective to permit the cam plate 201 to cover the opening 197 and so prevent undesired withdrawal of a key from the series of keys within the magazine before the key 171 is inserted through the slots 153, 155.

In utilizing a magazine of the construction shown in Figs. 7 to 13 inclusive in a system such as that described in connection with Figs. 1 and 2 and in cooperation with tour stations of the construction described in connection with Figs.

3 to 6 inclusive, it is preferable that the form of the keys of the set of "yellow" keys which are adapted to be contained within the magazine be different from that of the set of "white" keys for operating the transmitting station which are insertable in the key channel 93 of the tour station. By suitably proportioning these keys serving the two purposes described as to thickness and as to the width of the head at the top thereof and by making the head different, for example, rectangular as in Fig. 3 at the upper edge and with parallel side edges and sloping bottom edges for the "white" transmitting station keys and trapezoidal for the "yellow" keys as in Fig. 10 with the widest or base dimension of the trapezoid different from the width of the head of the "white" key, these widths being suitably chosen with respect to the width of the key channel between the lateral walls thereof, it is possible to prevent insertion of a "white" key in the magazine in such a manner as to effect operation of the magazine and, as well, to prevent insertion of the "yellow" keys in the key channel of the tour station in such a way as to effect operation of the tour station for release of a "white" key therefrom.

In Figs. 14 to 17 inclusive is shown a modification of the key magazine of the invention. This magazine is formed with a casing 211. Pivotally supported on a pin 213 carried at its ends in the front and back walls of the casing 211 is a member 215 biased by helical spring 217 toward the left in Figs. 14, 15 and 17. The spring 217 extends about a pin 218 rigidly fastened in the upper end of the pivoted member 215. The right hand end of the pin 218 extends into a recess 219 in a guide member 221 fastened in the end wall of the casing 211, a washer 222 being provided between the spring 217 and the left hand end of the member 221. The upper portion of the pivoted member 215 is rounded at 223 to provide space for insertion of a key between the set of five keys contained within the magazine and the member 215. Such insertion is accomplished through a slot 225 in the upper wall of the casing 211.

Such insertion, however, can only take place when a cover 227 having an end extension 228 for lifting by hand is moved counterclockwise in Fig. 14 pivotally on a bolt 229 supported in the front and back walls of the casing 211. Lifting of the cover 227 uncovers the slot 225 and also uncovers a pair of openings 231 in the upper wall of the casing 211 adjacent the opposite end 55 of the series of keys in the magazine from the member 215. The cover 227 carries a pair of fingers 233 shown in Figs. 14 and 16 respectively registering with the openings 231. When the cover is in the closed position, as shown in Fig. 14, these fingers 233 extend downwardly within the casing adjacent the wall 235 thereof. Adjacent this wall 235 in the bottom wall 236 of the casing an opening 237 is provided for withdrawal from the magazine, for example, of the "yellow" key for the next tour upon insertion through the slot 225 of the "yellow" key which has been used in the tour just completed, as above described. The action of the set of keys within the magazine upon insertion of such key through the slot 225 is 65 similar to that described in connection with Figs. 7 to 13 inclusive. In the embodiment shown in Figs. 14 to 17 inclusive, however, adjacent the opening 237 the bottom wall 236 of the casing is formed with a slightly upturned lip 239. The 75 upper end, that is, the head of the key 240, being

engaged by the wall 235 when the cover 227 is lifted and a key is inserted through the slot 225, pressure of the inserted key upon the surface 223 and against the adjacent key 241 acting against the bias of the spring 217 tends to force the series of keys within the magazine toward the left in Fig. 14. By suitably forming the lip 239, this pressure may produce lifting of the toe of the key 240 over the lip 239 to move the key 240 into position above the opening 237. The inserted key may be pushed downwardly until the head is within the slot 225 and the pressure of the spring 217 may be effective to hold the key 240 flat against the wall 235, there now being six keys within the magazine.

As shown in Figs. 14, 15 and 17 fastened upon the cover 227 are pins 243 in such position as to pass into the slot 225 when the cover is moved to the closed position shown in Fig. 14. These pins will bear upon the head of the inserted key, to move it downwardly fully to the position shown in Fig. 14 adjacent the series of keys already in the magazine. During the closing movement of the cover 227, however, the fingers 233 bear upon the upper edge of the key 240, which, as has been explained, is in contact with the wall 235. The key 240, now in position over slot 237, is pushed by the fingers 233 so that the end of the key protrudes through the opening 237. The key then may be withdrawn by the watchman.

In order to prevent accidental withdrawal or falling of the key through the opening 237, preferably a pair of springs 245 are supported on the bottom wall 236 of the casing for engaging the head of the key, the shank of the key passing between these springs and through the opening 237. The form and resistance of the springs 245 are such that, while holding the key 240 against accidentally falling from the magazine, the watchman may readily withdraw the key by pulling on the shank thereof.

The means of support of the tour stations and the magazines may be varied to suit different conditions and to prevent theft and tampering with these devices. In the embodiments which have been described, flanges merely have been shown through which fastening means may be passed for attachment to the walls of the building or other suitable supports. These means of support are not in themselves part of the invention but the constructions of the casings 91, 140 and 211 of the tour station and magazines are such that access to the interior is made impossible or so difficult as to prevent improper operation or tampering with the devices which would enable a watchman or an unauthorized person to effect without detection a fake operation of the system while apparently securing the proper operation thereof. Such constructions to prevent tampering are auxiliary to the essential broad and specific features of the invention which insure that the watchman must make his tour in the manner predetermined by the sets of keys which are utilized for operation of combination changing locks, one set in the embodiments so far described being utilized for the operation of the transmitting station lock and a supplemental set of different form being utilized for the operation of the tour station locks, the proper sequence with respect to these supplemental tour station keys being secured with the aid of the magazine.

In Fig. 18 is diagrammatically shown a modification of the system of the invention in which

a series of magazines is utilized in cooperation with the tour stations. Both of these devices may be of the constructions above described. In this modification, however, only one set of keys, that is, a set associated with only a single series of combinations of a combination changing lock, is utilized. As will be apparent from further description, the term "one set of keys" is intended to include a plurality of like sets. In the system of Fig. 18, it is possible to operate the tour stations to change the combination of the locks, provided therein, corresponding to locks 20 of Figs. 1 and 2 without the aid of a different set of keys, such as the "yellow keys" which have been described in connection with the systems of Figs. 1 and 2 as distinguished from the "white" keys. In this system the keys may all be said to belong to the "white" set of keys.

As shown in Fig. 18, each of the tour stations 250 distributed about the area to be surveyed may have associated therewith a magazine 251. The transmitting station 253 also has associated therewith a magazine 255. The locks 257 of the tour stations 250 and the lock 259 of the transmitting station 253 all are operable by the same set of six keys. For operation of the lock of a tour station 250 with a given key, for example, key 1 to operate tour station #261, this key may be withdrawn from the first magazine #271. After such operation of the lock of tour station #261, this key is inserted in the key channel of station #261 and functions therein in the manner described in connection with Figs. 1 and 2 to release another key 6 for operation of the lock in a succeeding combination. This key 6, however, in the system of Fig. 18 is not inserted in the key channel of the next tour station #262 in the manner described in connection with Figs. 1 and 2. Instead, it is inserted in the magazine #272 associated with tour station #262. Such insertion, as will be understood from the description of the operation of the magazines given above, for example, of Figs. 7 to 13 inclusive, is effective to secure withdrawal from the magazine #272 of another predetermined key 2 of this set of keys, adapted for operation of the locks 257, 259. The key 2 so withdrawn from the magazine then is utilized to operate tour station #262.

After operation of tour station #262 by key 2, this key 2 is inserted in the key channel of tour station #262 and another key 1 of the set of keys is withdrawn from tour station #262. This other key 1 so withdrawn from the channel of the tour station #262 is not, however, inserted in the key channel of the succeeding tour station #263 but is inserted in a key magazine #273 associated with tour station #263 to secure withdrawal from magazine #273 of still another predetermined key 3 of the set and this key 3 is utilized for operation of tour station #263 and then is inserted in the key channel thereof to release another key 2 therefrom. These operations are carried out in this manner for the other tour stations #264 and #265 and magazines #274 and #275 associated therewith until the last tour station #265 is operated by key 5 withdrawn from magazine #275, this key being inserted in tour station #265 to release key 4 therefrom. Key 4 withdrawn from the last tour station is inserted in magazine 255 associated with the transmitting station 253 to secure withdrawal from the magazine 255 of another key 6 of the set of keys, this key 6 being utilized for operating the transmitting station 253. Key 6 after such operation is not inserted in a key channel since the trans-

mitting station is not provided with a key channel as are the tour stations 250. This key 6 is carried by the watchman to the magazine #271 associated with the first tour station #261 and is inserted in this magazine to secure withdrawal of another key 2 of the set of keys, this key so withdrawn being utilized to operate this first tour station #261 in the second round or tour. The series of steps is repeated in the second tour in the manner just described. The keys withdrawn as above described are shown stippled in Fig. 18.

TABLE II
Magazine and tour stations

In Table II the numbers in parenthesis, e. g., (5), indicates the keys inserted in the magazine #271 to #275 inclusive or in the key channels of the tour stations #261 to #265 inclusive. The key at the bottom of the column for each such magazine or station is the key withdrawn upon insertion of the key indicated in ( ). The keys withdrawn at magazine 255 are used to operate the transmitting station 253 and then are inserted in magazine #271 to begin the next tour.

It will be understood from a consideration of the arrangement of the keys in the magazines 251 and 255 of Fig. 18 and by comparison with Table II that the insertion of a given key in a magazine insures the withdrawal of a predetermined key of the set and the insertion of this withdrawn key in the key channel of a tour station associated with the magazine insures the withdrawal of a key which may be inserted in the magazine associated with a succeeding tour station again to insure the withdrawal of a predetermined key for operation of this next tour station. It also will be apparent from a consideration of Table II that with five tour stations as shown in Fig. 18 and one transmitting station, the cycle of tours is repeated upon the completion of six tours utilizing a plurality of duplicate sets of keys which are distributed in the magazines and in the tour stations of the system.

20 It will be apparent that in the particular embodiment shown in Fig. 18 for which Table II shows the successions of keys inserted and withdrawn, eleven duplicate sets of keys, each set consisting of six keys corresponding to the six combinations of the combination changing lock, are required.

25 The system shown in Fig. 18 is advantageous for conditions requiring the survey by a watchman where it is difficult or otherwise disadvantageous to provide for signals to be given at a central office. It will be understood from the detailed description of tour stations and the magazines given above that these devices are highly fool proof and that the watchman must operate the system in the manner described in order that he shall always have the proper key for the operation of the locks of the tour stations and the transmitting station the combinations of which are changed in each operation.

30 40 It will be apparent from inspection of Fig. 18 that the magazines 251 may be divided into two sections and that these sections may be located in different locations on the site or area to be surveyed by the watchman. Thus, the upper portion of the magazine #271 containing the series of keys 4, 3, 2, 1, 6 in Fig. 18 may be located in a separate place from the section of this magazine which contains the series of keys 5, 4, 3, 2, 1. In such cases, it is merely necessary that when the key 6 is withdrawn by the watchman from the upper section upon insertion of a key 5 therein, he may carry the key 6 to the second section of the magazine. Upon insertion of this key 6 in this second section, key 5 may be withdrawn from this second section and used in the operation of the associated tour station #261 as above described. This tour station #261 may be at a different location from either of the sections of the magazine, the association being that which insures the proper sequence of insertion and withdrawal of keys and not necessarily of adjacency or a mechanical connection. The magazine 255 associated with the transmitting station 253 may be similarly divided. Thus, it will be understood that by dividing the magazines 251 and 255 in Fig. 18, seventeen locations may be provided for which the watchman must visit in making his tour in order that he may secure the proper key for operation of the transmitting station. This transmitting station may be of any suitable type which transmits a routine signal to a central office or records the operation thereof by suitable auxiliary devices. Moreover, this transmitting station itself may serve as the eighteenth

tour station in the system of Fig. 18 and may be located in any location which it is desired that the watchman shall visit in his survey.

Within the scope of the invention in another modification thereof, a plurality of magazines without the association therewith of tour stations having key channels for receiving keys of a set of keys for a single series of combinations may be utilized in cooperation with a transmitting station. As a simple example of this modification in Table III is given the tabulation of the keys of a set of four keys contained in a plurality of magazines. In each tour the key, of the three keys in each magazine, which is to be withdrawn therefrom is shown at the bottom of the respective columns for each tour. In tour No. 1, for example, upon insertion of key 4 in magazine #1 key 1 is withdrawn therefrom and is inserted in the next magazine #2 to secure withdrawal from this magazine #2 of key 2 for insertion in magazine #3. These steps are continued through the successive magazines until from the last magazine #5 a key 1 is withdrawn which may be utilized to operate the lock of a transmitting station. This key 1 is then inserted in magazine #1 to release key 2 in tour No. 2. The successive insertions and withdrawals of the keys in the successive tours will be understood from Table III.

TABLE III
Magazines as tour stations
Designation of keys distributed in magazines

	1	2	3	4	1

The above table shows a system for five stations using a set of four keys, three (with duplicates) in magazines, one in hand. The key withdrawn from each magazine, the bottom key of the three in each magazine in each tour, is inserted in the next magazine. The key withdrawn at the last magazine and then inserted in the first magazine is shown in ( ). The number of magazines equals one plus the number of keys in the set.

In this embodiment of the invention a sufficient number of magazines must be utilized to insure that the proper key is obtained for operation of the transmitting station and in the ordinary case an extra magazine will be utilized which will contain a set of the keys which in effect replace the duplicate set of keys which are releasably retained within the tour stations 250 of Fig. 18. In this modification, as in that of Fig. 18,

however, the succession of keys inserted and withdrawn from the magazines must be maintained by the watchman in order that he shall be able to have in hand the proper key for operating the transmitting station and this requires that he visit the locations at which the magazines are placed so that the desired survey of the site by the watchman is thereby insured.

Summarizing the above description it now will be more clearly understood that the systems of the invention utilize at least one tour station and a transmitting station, at least this transmitting station having a lock provided with means for changing the combination thereof in each operation of the lock and requiring a different predetermined key of a set of keys for the next operation of the lock. Whether the tour station consists of a magazine or a device having a key channel and operable in the manner above described, these tour stations provide means for releasably retaining a key which is adapted to operate the transmitting station lock to change the combination thereof. The tour stations of either type, that is, the magazine or the device having a key channel, provide means which is actuatable by a succeeding key of a set to release the retained key so that the succession may be carried out in the manner described to provide for operation of the transmitting station with the key corresponding to the combination to which its lock was changed at the end of the previous tour.

The systems of the invention, as above described, moreover, provide a container for a "supplemental" set of keys which are capable of operating the lock of at least one station of a system to change the combination thereof, this containing means being actuatable by a key of the "supplemental" set to liberate therefrom a succeeding key of this "supplemental" set. In the embodiment of the invention which utilizes a set of "yellow" keys supplemental to the set of "white" keys which are adapted to operate the transmitting station, the supplemental "yellow" keys are different from the "white" transmitting station keys. In the embodiment of Fig. 18, however, as well as the modification thereof described which utilizes only the magazines and a transmitting station, the "supplemental" keys are of the same form, that is, they are capable of operating the same lock, at least the transmitting station lock, as are the keys which are passed in succession through the key channels of the tour stations. Where the tour stations are provided with locks, this "supplemental" set of keys as well as the other keys which are distributed through the system are the same, that is, they correspond respectively to the same combinations of the lock, so that all of the locks of the tour stations and that of the transmitting station may be alike.

While the system of the invention has been described in four modifications thereof, other modifications are possible within the scope thereof and other uses may be made of the devices which are utilized in the systems of the invention. For example, the magazines of the construction of either Figs. 7 to 13 inclusive or 14 to 17 inclusive may be utilized for containing the different keys of a set of keys corresponding to the combinations of a lock the combination of which may be changed. Such magazines are useful for example, where the locks of a hotel or other public building require occasional or frequent change of the combination thereof in order to prevent opening of doors or other closures by

keys retained by guests or others leaving the premises or the employ of the owners. By arranging in the magazine in the proper order, that is, the order of the change of the combinations of the lock, the several keys corresponding to the different combinations, insertion in the magazine of a key of the set of keys will secure withdrawal therefrom of the proper key for the next combination without search through the magazine or trial of the different keys to secure the desired key. In such use, however, ordinarily the lock on the door or closure would be so constructed that it may be operated by one of the keys of the set without changing the combination in each operation of the lock. The lock, however, would be constructed so that its combination may be changed by a master key when such change is desired.

The magazine utilized for containing such a set of keys itself may be provided with a combination changing lock operable in succession by the keys of the set of keys contained therein. Thus, to secure the next key for operation of the lock of the door of the hotel or other closure in the combination to which it is changed by the master key or otherwise, the key previously used for operating this door lock may be used to unlock the magazine, for example, of the type shown in Figs. 7 to 13 inclusive. After opening the magazine, this key may be inserted therein as described in connection with Figs. 7 to 13 inclusive to condition the desired next key for withdrawal therefrom. The magazine may be provided with a lock having a snap latch, as shown in Fig. 7, so that the door of the magazine may be snapped closed after such insertion and the desired next key withdrawn. The combination of the magazine lock will have been changed in the operation thereof to open the magazine and thus will require this next key just withdrawn when it is desired again to open the magazine to secure therefrom the proper key for operation of the door or closure when the combination of its lock again has been changed.

In the systems of Figs. 1, 2 and 18 wherein one or more magazines are utilized, these magazines constructed, for example, as shown in Figs. 7 to 13 inclusive may be provided with combination changing locks. It will be apparent from a consideration of Tables I, II and III in connection with Figs. 1, 2 and 18, that a key withdrawn from a magazine for insertion in the key channel of a tour station or for insertion in a succeeding magazine insures the withdrawal of a predetermined key from such succeeding tour station or magazine. It also is apparent that the successive combinations to which the keys so withdrawn correspond progress in regular order. It, therefore, is possible in the systems of the invention utilizing magazines initially to set the combination of the combination changing lock of the magazine for operation of a given key, for example, key 6 withdrawn from tour station #261 to operate the lock of magazine #272, this key being inserted in this magazine as above described. In the next tour key 1 which is the next key in order will be withdrawn from tour station #261 for insertion in magazine #272 and may be utilized for operation of the lock of magazine #272 to open this magazine before such insertion and concomitantly to change the combination of its lock.

Other uses and other variations from the particular arrangements and devices hereinabove disclosed may be made by those skilled in the art while utilizing the features of the invention which

have been summarized above and otherwise disclosed herein. All such variations and modifications are within the scope of the invention and are intended to be covered by the appended claims.

5 I claim:

1. A watchman's tour system comprising at least one tour station, a transmitting station, at least said transmitting station having a lock provided with means for changing the combination thereof in each operation of the lock and requiring a different predetermined key of a set of keys for the next operation of the lock, means associated with said tour station for releasably retaining a key of said set of keys for said transmitting station lock and actuatable by a succeeding key of said set to release said retained key for operation of said lock of said transmitting station, and means for containing a supplemental set of keys capable of operating in succession the lock of at least one of said stations to change the combination thereof and actuatable by a key of said supplemental set to liberate from said containing means a succeeding key of said supplemental set.
2. A watchman's tour system comprising a plurality of tour stations, a transmitting station, each of said tour stations having a lock provided with means for changing the combination thereof in each operation of the lock and requiring a different predetermined key of a set of keys for the next operation of the lock, said transmitting station having a lock provided with means for changing the combination thereof in each operation of the lock and requiring a different predetermined key of a set of keys for the next operation of the lock, means respectively associated with said tour stations for releasably retaining a key of said set of transmitter station keys and actuatable by a succeeding key of said set and upon operation of the respective tour station lock to release said retained key, and means for containing a supplemental set of keys capable of operating in succession the locks of said tour stations to change the combination thereof and actuatable by a key of said supplemental set to liberate from said containing means a succeeding key of said supplemental set for operation of the next tour station.
3. A watchman's tour system comprising a plurality of tour stations, a transmitting station, said tour stations and said transmitting station each being provided with a combination changing lock requiring a different predetermined key for the next operation of the lock, the locks of said tour stations being different from said transmitting station lock and requiring a set of keys for the successive operations of said tour station locks different from a set of keys capable of operating in succession the lock of said transmitting station, means respectively associated with said tour stations for releasably retaining a key of said set of keys for said transmitting station lock and actuatable by a succeeding key of said set of transmitting station keys to release said retained key, and means for containing a supplemental set of keys capable of operating in succession the locks of said tour stations to change the combination thereof and actuatable by a key of said supplemental set to liberate from said containing means a succeeding key of said supplemental set.
4. A watchman's tour system comprising a plurality of tour stations, a transmitting station, 75 said tour stations and said transmitting station

each being provided with a combination changing lock requiring a different predetermined key of a set of keys for the next operation of the lock, the locks of said tour stations and said transmitting station being alike and being adjusted respectively to the combinations corresponding to the keys of said set of keys, means respectively associated with said tour stations for releasably retaining a key of said set of keys and actuatable by a succeeding key of said set to release said retained key, and means for containing a duplicate set of keys capable of operating said locks in succession to change the combinations thereof and actuatable by a key of said set of duplicate keys to liberate from said containing means a succeeding key of said duplicate set.

5. A watchman's tour system comprising a plurality of tour stations, a transmitting station, said transmitting station having a lock provided with means for changing the combination thereof in each operation of the lock and requiring a different key of a set of keys for the next operation of the lock, means associated with each of said tour stations for releasably retaining a key of said set of transmitter station keys and actuatable by a succeeding key of said set to release said retained key, said tour stations respectively having locks operable by a key and operatively connected to said means for releasing said retained transmitting station key to effect such release upon operation of the respective tour stations, and means containing a supplemental set of keys capable of operating in succession the locks of said tour stations and actuatable by a key of said supplemental set to liberate from said containing means a succeeding key of said supplemental set for operation of the next tour station.

6. A watchman's tour system comprising a plurality of tour stations, a transmitting station, said tour stations and said transmitting station each being provided with a combination changing lock requiring a different predetermined key of at least one set of keys for the next operation of the lock, each of said tour stations being constructed with a key channel adapted to receive for passage therethrough in succession the keys of the set of keys required for operation of said transmitting station, each of said tour stations being provided with means cooperating with said key channel for releasably retaining a transmitting station key inserted in said channel, each of said tour stations being provided with means cooperating with said key retaining means and with the lock of said tour station for effecting release of said retained key upon insertion in said channel of a succeeding transmitting station key and upon operation of the lock to change the combination, and means for releasably retaining in a predetermined order the keys required for operation of said tour station locks.

7. A watchman's tour system comprising a plurality of tour stations, a transmitting station, said tour stations and said transmitting station each being provided with a combination changing lock requiring a different predetermined key of a set of keys for the next operation of this lock, the locks of said tour stations being alike and being different from said transmitting station lock and requiring a set of keys for the successive operations of said tour station locks different from a set of keys capable of operating in succession the lock of said transmitting station, means respectively associated with said tour stations for releasably retaining a key of said set of

keys for said transmitting station lock and actuatable by a succeeding key of said set of transmitting station keys to release said retained key, said means being incapable of actuation by a key of said set of tour station keys, and means for releasably retaining in a predetermined order the keys of said set of tour station keys and actuatable by a key of said set of tour station keys to liberate from said retaining means a succeeding key of said set of tour station keys.

8. A watchman's tour system comprising a plurality of tour stations, a transmitting station, said transmitting station having a lock provided with means for changing the combination thereof in each operation of the lock and requiring a different predetermined key of a set of keys for the next operation of the lock, each of said tour stations being constructed with a key channel adapted to receive for passage therethrough in succession the keys of said set of transmitting station keys, means in each tour station cooperating with the key channel thereof for releasably retaining a transmitting station key inserted in said channel, means cooperating with said key channel and said key retaining means and actuatable upon insertion in said channel of a succeeding transmitting station key for effecting release of said retained key, and a magazine for containing a set of keys capable of operating said transmitting station lock to change the combination thereof and constructed to release a transmitting station key for insertion in a succeeding tour station channel upon insertion in said magazine of the transmitting station key released from the channel of the preceding tour station.

9. A watchman's tour system as defined in claim 8 in which said magazine is constructed to contain all except one of said set of keys for operating said transmitting station lock and for insertion in said magazine of only one key at a time in a predetermined relation to the other keys contained therein concomitantly with liberation from said magazine of a predetermined key of said keys contained in said magazine.

10. A watchman's tour system as defined in claim 2 which comprises an alarm signal device, an auxiliary station constructed to be operated by a key of a set of keys capable of operating the locks of said tour stations, and means actuated upon operation of said auxiliary station and operatively connected to said alarm signal device for operating said alarm signal device.

11. A watchman's tour system as defined in claim 1 which comprises a routine signal device, and means actuated upon operation of said lock of said transmitting station and operatively connected to said routine signal for operating said routine signal device.

12. A watchman's tour system as defined in claim 2 which comprises an alarm signal device and a routine signal device, an auxiliary station constructed to be operated by a key of a set of keys for operating said tour station locks, means actuated upon operation of said auxiliary station and operatively connected to said alarm signal device for operating said alarm signal device, and means actuated upon operation of said lock of said transmitting station for operating said routine signal device.

13. A watchman's signalling system comprising a plurality of tour stations each having a switch operable from one to the other of two contact positions, a signal device, circuit means connecting said signal device to the switch of each

station, said circuit means being controlled by the relative positioning of said switches to establish one or another of two circuits including said signal device, the inclusion of said signal device in one of said circuits establishing an alarm condition and the inclusion of said signal device in the other of said circuits effecting a routine signal, a transmitting station having a lock provided with means for changing the combination thereof in each operation thereof and requiring a different predetermined key of a set of keys for the next operation of the lock, means associated with each tour station for releasably retaining a key of said set of keys for said transmitting station and actuatable by a succeeding key of said set to release said retained key, and means for containing a supplemental set of keys capable of operating said tour stations to operate the switches thereof from one position to the other of said two contact positions, said containing means being actuatable by a key of said supplemental set to liberate from said containing means a succeeding key of said supplemental set.

14. A watchman's signaling system comprising a plurality of tour stations, each having a switch operable from one to the other of two contact positions, a signal device, circuit means connecting said signal device to the switch of each station, said circuit means being controlled by the relative positioning of said switches to establish one or another of two circuits including said signal device, the inclusion of said signal device in one of said circuits establishing an alarm condition and the inclusion of said signal device in the other of said circuits effecting a routine signal, each of said tour stations having a lock provided with means for changing the combination thereof in each operation of the lock and requiring a different predetermined key of a set of keys for the next operation of the lock, said lock of each tour station being operatively connected to said switch to operate said switch from one to the other of said two contact positions upon operation of the lock of said tour station, a transmitting station having a lock provided with means for changing the combination thereof in each operation thereof and requiring a different predetermined key of a set of keys for the next operation of the lock, means associated with each tour station for releasably retaining a key of said set of keys required for operation of said transmitting station lock and actuatable by a key of said set to release said retained key, and means for containing a supplemental set of keys capable of operating in succession the locks of said tour stations to change the combination thereof, said containing means being actuatable by a key of said supplemental set to liberate from said containing means a succeeding key of said supplemental set.

15. A watchman's signaling system as defined in claim 2 in which said tour station locks and said transmitting station lock are different from each other and require two different sets of keys for operation thereof, said means for containing said supplemental set of keys capable of operating said tour station locks being incapable of receiving a transmitting station key.

16. A watchman's tour system comprising at least one tour station, said tour station having a lock provided with means for changing the combination thereof in each operation of the lock and requiring a different predetermined key of a set of keys for the next operation of said lock, a key magazine adapted to contain all except one

of said set of keys and provided with means actuated upon insertion in said magazine of the key utilized for operation of a tour station lock in a completed tour concomitantly with change in the combination of said lock for effecting release from said magazine of the key required for operation of a tour station lock in the next tour.

17. A watchman's tour system comprising a plurality of tour stations, each of said tour stations having a lock provided with means for changing the combination thereof in each operation of the lock and requiring a different predetermined key of a set of keys for the next operation of said lock, the locks of all said tour stations being alike and being adjusted respectively to the different combinations of said lock corresponding to the keys of said set of keys, a key magazine adapted to contain all except one of said set of keys and provided with means actuated upon insertion in said magazine of the key utilized for operation of a tour station lock to change the combination of said lock in a completed tour for effecting release from said magazine of the key required for operation of a tour station lock in the next tour.

18. A tour station for a watchman's tour system comprising a member operable in the operation of said station, means for releasably retaining a key of a set of keys required for operation of a lock associated with said system and actuatable by another key of said set to condition said retaining means for release of said first key, means actuated upon initial operation of said member and cooperating with said retaining means initially to prevent release of both said keys from said tour station, and means actuated upon completion of the operation of said member and operatively connected to said retaining means and to said cooperating means to effect release of said first retained key while maintaining retention of said other key.

19. A tour station for a watchman's tour system comprising a member operable in the operation of said station, means providing a key channel adapted to receive for passage therethrough in succession the keys of a set of keys required for operation of a lock associated with said system, means cooperating with said key channel for releasably retaining a key of said set of keys inserted in said channel and actuated upon insertion in said channel of a second key of said set of keys for conditioning said retained key for release thereof, means actuated by said member initially in the operation of said station and cooperating with said retaining means initially to prevent release of both keys from said tour station, and means actuated by said member in the completing operation thereof and operatively connected to said retaining means and to said cooperating means to effect release of said first retained key from said channel while maintaining retention in said channel of said second key inserted therein.

20. A tour station for a watchman's tour system as defined in claim 19 which comprises means actuated concomitantly with initial operation of said member and cooperating with said member to prevent completion of the operation thereof and actuated upon insertion of said second key in said channel to actuate said retaining means to condition said first key for release.

21. A tour station for a watchman's tour system as defined in claim 19 which comprises a lock operatively connected to said member to effect

initial operation of said member in the operation of said station in one direction of rotation of a key inserted in said lock, said lock and said key being constructed to prevent withdrawal of said key from said lock in the position to which said key is moved in the initial operation of said member, said lock being operatively connected to said member to effect completion of the operation of said station by said member in the return movement of said key in said lock to the initial position thereof, said key being capable of being withdrawn in said initial position thereof.

22. A tour station for a watchman's tour system comprising a member operable in the operation of said station, means providing a key channel adapted to receive for passage therethrough in succession the keys of a set of keys required for operation of a lock associated with said system, a key engaging finger supported to be movable to and from a position for engaging a key contained within said channel, means actuated by a key inserted in said channel and operatively connected to said finger for moving said finger from the position of engagement of the key within said channel, a second finger located along said channel from said first finger in the direction of discharge of the key from said channel and supported to be movable to and from a position for engaging a second key contained within and along said channel from said first key, means actuated by said member upon initial operation of said member in the operation of said station and operatively connected to said second finger to effect movement of said second finger into key engaging position with respect to said channel, said means actuated by said first key cooperating with said means actuated by said member to prevent completion of the operation of said member except when said first finger is moved from key engaging position by insertion of said key in said channel, said second finger being actuated by said means operated by said member in the completing operation of said station to release said second key for withdrawal from said channel concomitantly with actuation of said first finger by said inserted key.

23. A watchman's tour system comprising a plurality of key magazines located respectively at stations to be visited by the watchman, each magazine being adapted to contain selected keys of a set of keys, said selected keys being arranged in said magazines in a predetermined order, the number of keys of said set being one less than the number of magazines, the number of keys selected to be contained in each magazine being one less than the number of keys in said set, said magazine being provided with means actuated upon insertion therein of a key of said set in its predetermined relation in said order to the other keys contained within the magazine for effecting release from said magazine of the succeeding key of said set, the keys in the respective magazines being different from those of the magazine adjacent thereto in a given succession of said magazines by the inclusion of said inserted key and the exclusion of said released key.

24. A watchman's tour system comprising a station to be visited by the watchman having a lock provided with means for changing the combination thereof in each operation of the lock and requiring a different predetermined key of a set of keys for the next operation of said lock, and a key magazine for containing selected keys of said set of keys arranged therein in the order of the successive combinations of said lock, said

magazine being provided with means actuated upon insertion therein of a key of said set in its predetermined relation to the other keys of said set in said order for effecting release from said magazine of the key for the succeeding operation of said lock to change the combination thereof.

25. A watchman's tour system comprising a plurality of stations to be visited by the watchman, each station having a lock provided with means for changing the combination thereof in each operation of the lock and requiring a different predetermined key of a set of keys for the next operation of said lock, a key magazine for each station for containing selected keys of said set arranged therein in the order of the successive combinations of said lock, said magazines being provided with means actuated upon insertion therein of a key of said set in its predetermined relation to the other keys of said set in said order for effecting release from said magazine of a predetermined key of said set, and means associated with said station for releasably retaining a key of said set of keys and actuatable by another key of said set to release said retained key, said keys in said magazines and in said retaining means being arranged consecutively in said order of the successive combinations of said locks.

26. A watchman's tour system comprising a plurality of stations to be visited by the watchman, each station having a lock provided with means for changing the combination thereof in each operation of the lock and requiring a different predetermined key of a set of keys for the next operation of the lock, the locks of said stations respectively being set at the different successive combinations thereof, a key magazine for each station for containing selected keys of said set arranged therein in the order of the successive combinations of said lock, said magazine being provided with means actuated upon insertion therein of a key of said set in its predetermined relation to the other keys of said set in said order for effecting release from said magazine of a predetermined key of said set, and means associated with each station for releasably retaining a key of said set and actuatable by another key of said set to release said retained key, said key retained in said station by said retaining means being the succeeding key in said order in relation to the key released from said station in the preceding operation of the lock thereof, said predetermined key released from said magazine associated with said station being the succeeding key in said order to said retained key, whereby upon actuation of said retaining means by said predetermined key said retained key is released for insertion in the magazine of the succeeding station in said order of said combinations.

27. A tour station for a watchman's tour system comprising a member operable in the operation of said station, means for releasably retaining a key of a set of keys required for operation of a lock associated with said system and actuated by said member upon initial operation of said member to effect release of said key from said retaining means, and means actuated by said retaining means for engaging said member after said initial operation thereof to prevent completion of the operation of said member in the operation of said tour station, said retaining means being actuatable by another key of said set to effect disengagement of said engaging means from said member to permit completion of the operation of said member.

28. A tour station for a watchman's tour system

comprising a member operable in the operation of said station, means for releasably retaining a key of a set of keys required for operation of a lock associated with said system and actuated by said member upon initial operation of said member to effect release of said key from said retaining means, means actuated by said retaining means for engaging said member after said initial operation thereof to prevent completion of the operation of said member in the operation of said tour station, said retaining means being actuatable by another key of said set to effect disengagement of said engaging means from said member to permit completion of the operation of said member, and means actuated by said member upon said initial operation of said member for intercepting said key released from said retaining means to prevent withdrawal thereof from the station and actuated by said member upon completion of the operation of said member to effect release of said intercepted key for said withdrawal thereof.

29. A tour station for a watchman's tour system comprising a member operable in the operation of said station, means providing a key channel adapted to receive for passage therethrough in succession the keys of a set of keys required for operation of a lock associated with said system, a key retaining element cooperating with said key channel and movable with respect thereto to and from positions respectively for retaining a key in said channel and for releasing the key for passage through said channel, said element being actuatable by another key of the set from key retaining position to key releasing position upon insertion of said other key in said key channel and adapted to return to key retaining position upon passage of said inserted key along said channel, said member being adapted to

actuate said element to key releasing position in the initial operation of said member and thereupon to release said element for return thereof to key retaining position, and means operatively connected to said element and movable from a position for engagement thereof by said member to a position of disengagement from said member upon said movement of said element from key retaining position to key releasing position, said means operatively connected to said element after said initial operation of said member being adapted to engage said member to prevent completion of the operation of said member while said element is in said key retaining position and disengaging said member for completion of the operation thereof concomitantly with movement of said element to the key releasing position upon insertion of said other key in said key channel.

30. A tour station for a watchman's tour system as defined in claim 29 comprising means actuated by said member upon said initial operation of said member for intercepting said key released from said retaining means to prevent withdrawal thereof from said station and actuated by said member upon completion of the operation of said member to effect release of said intercepted key for said withdrawal thereof.

EDWARD A. SCHACHINGER.
